(57) **CLAIM**

The ornamental design for a pair of limb protectors for a pet, as shown and described.

DESCRIPTION

FIG. 1 is a top, front perspective view of a rear limb protector from a pair of limb protectors for a pet showing my new design;

FIG. 2 is a top, front perspective view of a front limb protector from the pair of limb protectors for a pet;

FIG. 3 is a top plan view of the rear limb protector of FIG. 1;

FIG. 4 is a front elevation view thereof;

FIG. 5 is a bottom plan view thereof;

FIG. 6 is a top plan view of the front limb protector of FIG. 2;

FIG. 7 is a front elevation view thereof;

FIG. 8 is a bottom plan view thereof;

FIG. 9 is a cross-sectional view of the rear limb protector, taken in the direction of line 9-9 of FIG. 3;

FIG. 10 is a cross-sectional view of the front limb protector, taken in the direction of line 10-10 of FIG. 6; and,

FIG. 11 is a top, right perspective view of the pair of limb protectors for a pet, shown in a condition of use.

Right side view, left side view and rear view not shown are mirror images of the front view. In FIG. 11, the broken line showing of a dog depicts environmental structure only, and forms no part of the claimed design. The drawings are shaded to indicate contrasting surfaces.
